UNITED STATES PATENT OFFICE.

CARL FOSTER MOORE, OF CUSHING, OKLAHOMA.

BALE-TIE.

1,278,712.

Specification of Letters Patent. Patented Sept. 10, 1918.

Application filed February 27, 1918. Serial No. 219,416.

To all whom it may concern:

Be it known that I, CARL F. MOORE, a citizen of the United States, and a resident of Cushing, in the county of Payne and State 5 of Oklahoma, have made certain new and useful Improvements in Bale-Ties, of which the following is a specification.

My present invention relates generally to bale ties, and more particularly to a bale tie 10 buckle, my primary object being the provision of a simple, inexpensive buckle which will be effective and efficient in use, and which may be manufactured from a single piece of material bent to form.

15 A further object of my invention is the provision of a buckle of this type bent from a single length of material, in the bending of which all acute angles may be avoided so as to obviate danger of crystallization of the 20 metal.

In the accompanying drawing which illustrates several possible forms of my invention:—

Figure 1 is a perspective view of a portion 25 of a complete bale, illustrating the practical application of my invention.

Fig. 2 is a detailed perspective view of my invention, illustrating the same in position in use with the crimped end of the tie 30 band.

Fig. 3 is a detailed perspective view of my improved buckle, as manufactured in the first instance.

Fig. 4 is a sectional view through my invention in its position in use.

Fig. 5 is a detailed perspective view of a slightly modified form, and,

Fig. 6 is a similar view of another slightly modified form.

40 Referring now to these figures, my improved bale tie includes a tie band 10, as seen in Fig. 1, the ends of which are joined by a buckle generally indicated at 11 in this figure, and in the use of which buckle one 45 end of the tie band 10 is doubled back upon itself for some distance, as seen at 12, in Fig. 2, the opposite free end or extremity 13 of the band extending through a portion of the buckle and terminating beneath the same 50 with an angularly crimped portion 14, which assists in holding the band tightly in proper position, and which is brought about by virtue of the particular construction of the buckle to be now described.

55 Referring now particularly to Figs. 3, 4

and 5, illustrating slightly modified forms of the buckle, it will be noted that in each instance it is generally of 8-shape, and that it is formed of a single section of material, the extremities of which are terminated adjacent 60 to one another at a point approximately at the center of one of its end loops.

Thus with particular reference to Fig. 3, the section of material is bent to form one complete closed end loop 15, the extremities 65 16 and 17 terminating in spaced opposing relation approximately at the center of the other loop, with the intermediate extensions 18 and 19 crossing one another between the two loops, so that longitudinal strain will 70 have a tendency to draw the extremities 16 and 17 toward one another.

In the form shown in Fig. 5, this same construction is substantially carried out, in so far as the end loop 15^a and the crossed 75 intermediate extensions 18^a and 19^a are concerned, the extremities 16^a and 17^a being, however, in this case, slightly lapped.

In the form shown in Fig. 6, the single 80 section of material is bent to form one complete end loop 15^b and its intermediate portions 18^b and 19^b are bent around one another, reverting to the same side of the other end loop at an approximately central point of which the free extremities 16^b and 85 17^b terminate in spaced opposing relation, as in the construction shown in Figs. 2 and 3.

In each of these forms, the free extremities of the material approximately central of one of the end loops are bent or curved 90 out of the plane of the opposite end loop, as may be seen particularly by reference to Fig. 4, so that after the tie band has been properly associated with the buckle and the extremity 13 of the said band passed 95 through the loop adjacent the free extremities of the buckle, the natural expansive pressure of the bale will force the buckle to bend or crimp the extremity of the band, as at 14, in Figs. 2 and 4, so that with the free 100 extremity 13 of the band beneath the intermediate portions of the buckle, and the crimped portion 14 of the band engaged against one end of the buckle, the band will be firmly and effectively held against displacement.

In use, one end of the bale band 10 is passed through the end loop 15, and its extremity 12 doubled back thereon between the band 10 and the bale it surrounds, and with 110

the buckle outstanding at an angle with respect to the bale, the free end 13 of the band is passed through the opposite end loop as far as possible, and the buckle then 5 rocked, as nearly parallel to the bale as possible, so that when the latter is released its expansive pressure will further tend to move the buckle to a position parallel with the outer surface of the bale, and thus its 10 one end loop and its intermediate cross bars will act as a lever to bend or crimp the bale band extremity 13, as indicated at 14 in Figs. 2 and 4, for the purposes above stated. It is to be understood that either of the 15 constructions shown in Figs. 3 and 6 may have their extremities lapped as indicated in Fig. 5, and that the construction, particularly that of Figs. 2, 3 and 5 obviates all abrupt bends and angles such as might be

calculated to promote crystallization of the 20 metal in the manufacture of the buckle.

It is obvious that the buckle is extremely simple and inexpensive and that in addition to its general effectiveness and efficiency in use, it provides for a great saving of material as compared to the buckles now in 25 general use.

I claim:

A bale tie buckle consisting of a single section of material bent substantially to an 30 8-shape, and one of the opposite end loops of which is bent out of the plane of the other end loop, for the purpose described.

CARL FOSTER MOORE.
